US00D953518S

(12) **United States Design Patent** (10) **Patent No.:** **US D953,518 S**
(45) **Date of Patent:** **** May 31, 2022**

(54) **PORTABLE MESH NEBULIZER**

(71) Applicant: **SHENZHEN IMDK MEDICAL TECHNOLOGY CO., LTD**, Shenzhen (CN)

(72) Inventor: **Changchun Xia**, Wenzhou (CN)

(73) Assignee: **SHENZHEN IMDK MEDICAL TECHNOLOGY CO., LTD**, Shenzhen (CN)

(**) Term: **15 Years**

(21) Appl. No.: **29/739,429**

(22) Filed: **Jun. 25, 2020**

(30) **Foreign Application Priority Data**

May 20, 2020 (CN) 202030235483.X

(51) **LOC (13) Cl.** **29-02**

(52) **U.S. Cl.**

USPC **D24/110**

(57) **CLAIM**

The ornamental design for a portable mesh nebulizer, as shown and described.

DESCRIPTION

FIG. 1 is a top, right side and rear perspective view of a portable mesh nebulizer showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawing depict portions of the portable mesh nebulizer that form no part of the claimed design.

1 Claim, 7 Drawing Sheets
